GUSTAV RUDOLF GOMPF, OF BERLIN, GERMANY

MANIFOLDING SALES BOOK

Application filed August 21, 1929, Serial No. 387,467, and in Germany January 28, 1927.

My invention relates to improvements in manifolding salesbooks, and more particularly in salesbooks of the type by means of which quadruplicate copies may be made. 5 The object of the improvements is to provide a salesbook of this type which can be readily handled, and in which the legends printed on corresponding sheets are always in exact register, and all the sheets are correctly numbered. 10 With this object in view my invention consists in superposing an opaque and a transparent ribbon of paper or the like, and reversely folding the same back and forth upon themselves in zig-zag fashion and so 15 that a pair of leaves of opaque paper jointed along their front edge envelop a pair of sheets of transparent paper likewise jointed at their front edge. By thus composing the book, the numbers and legends are always printed on 20 the sheets in a uniform way, and errors in assembling the sheets can not occur. Further, the use of the four leaves needed for recording a sale or making other memoranda can be readily pulled away from the pad and 25 torn off, after making the memorandum, and when pulling the said leaves from the pad simultaneously the upper section of the next set of leaves is bent away from the pad so 30 that the carbon sheets can be placed between the same.

Another object of the improvements is to provide a pad in which the carbon sheets can be readily placed into position between the leaves of paper, and with this object in view 35 my invention consists in jointing two carbon sheets to be used for making a memorandum in quadruplicate along one of its side edges, the fold of the carbon sheets being parallel to the direction in which the sheets of paper 40 are pulled from the pad, one of the carbon sheets being preferably held in position on the pad along its upper edge. In my improved pad both carbon sheets may be coated with ink at both faces, or only one of the 45 carbon sheets is coated at both sides, while the other sheet is coated at one side only.

For the purpose of explaining the invention an example embodying the same has been shown in the accompanying drawing in 50 which the same reference characters have

been used in all the views to indicate corresponding parts. In said drawing,

Fig. 1, is a plan view of the salesbook,

Fig. 2, is a sectional elevation taken on the line 2—2 of Fig. 1,

Fig. 3, is a sectional elevation taken on the line 3—3 of Fig. 1, the said figures showing the ribbons assembled, and

Fig. 4, is a perspective view showing some of the leaves pulled away from the pad for separating the leaves on which a memorandum has been made and preparing the pad for making a memorandum on the next set of sheets.

On a base plate *a* a book or pad is supported which is composed of two superposed ribbons *d* and *u* of paper or the like which are reversely folded back and forth upon themselves in zig-zag fashion, the ribbon *d* consisting of transparent paper, and the ribbon *u* of opaque paper. In the sectional elevations shown in Figs. 2 and 3 the upper leaves are slightly lifted away from the pad for more clearly showing the same and the carbon sheets placed between the same.

The memorandum is made in the usual way by writing on the uppermost leaf of opaque paper, and for making the copies on the second, third and fourth leaf carbon sheets *k*¹ and *k*² are provided, *k*¹ being coated at both 80 sides, while *k*² is coated only at its bottom side, the coating being indicated by dotted lines. Thus, when writing on the uppermost sheet *u* the top face of the carbon sheet *k*¹ reproduces the memorandum on the bottom 85 face of the second sheet indicated in Fig. 3 by the numeral 2, the said sheet being made from transparent paper, so that the record appearing on the back face of the sheet in mirror-script can be read from the top side 90 thereof. By the bottom face of the sheet *k*¹ the memorandum is reproduced on the third leaf 3. The carbon sheet *k*² which has a coating only on its bottom face reproduces the memorandum on the fourth sheet 4.

As will be best understood from Figs. 2 and 4, the leaves used for making the quadruplicate copies are assembled as follows:

For each record four leaves are needed which are folded in pairs and placed one 100

within the other. In Fig. 3 the said leaves are shown slightly lifted away from the body of the pad. A pair of leaves u of opaque paper having their fold v_k at the front side of the pad envelops a pair of leaves d of transparent paper having their fold likewise located at the front side of the pad. The upper leaf 2 of the inner pair is located below the upper leaf 1 of the outer pair, and the lower leaf 3 of the inner pair is located between the two sheets k^1, k^2 of carbon paper.

Along the rear side of the pad a spring fastener is provided which consists of two sheet metal strips b^1 and b^2 bent into angular form and a spring b^2 acting thereon, the strip b^2 bearing on the pad or book, and the strip b^1 clamping the upper carbon sheet k^1 between the same and the strip b^2 .

The carbon sheets k^1 and k^2 are jointed along their longitudinal sides by means of a fold f , the said fold being preferably located along the right hand side of the pad. The upper carbon sheet k^1 slightly projects beyond the rear margin of the sheet k^2 , so that it can be readily clamped between the sheet metal strips b^1 and b^2 .

When writing a memorandum on the pad the paper ribbons d and u are assembled in the manner shown in Figs. 1 to 3, and the carbon sheets are placed between the same. After writing the memorandum or recording the sale the uppermost leaves 1 and 2 are folded forwardly, the third leaf 3 is slightly lifted to permit the carbon sheet k^2 to be pulled laterally away from the pad, and the carbon sheets are swung rearwardly into the position shown in Fig. 4, the said carbon sheets being held on the pad by means of the fastener b^1, b^2 . Now the third and fourth leaves are pulled forwardly, which leaves carry along the first and second leaves I and II of the next set. Now the pad and the leaves pulled therefrom are in the positions shown in Fig. 4. Now the carbon sheet k^1 automatically places itself on the third leaf III of the next set. The leaves 1-4 are separated from the leaves I and II of the pad along the line T-T shown in Fig. 4, and the carbon sheet k^2 is inserted below the third leaf III which for this purpose is slightly lifted from the pad. After placing leaves I and II on the carbon sheet k^1 located on the top of the pad the book is ready for further use.

I claim:

1. A manifolding device comprising a pad consisting of a pair of continuous sheets folded reversely back and forth to form a series of sets of leaves in quadruplicate, the sheet which forms the inner leaves of each set being transparent and the other sheet being opaque, means associated with that end of the pad adjacent the free ends of the uppermost set of leaves for yieldably retaining the leaves in assembled relation whereby the

uppermost set of leaves and the succeeding set may be withdrawn from said means, the uppermost set detached, and the free ends of the succeeding set of leaves folded back upon the pad to place the latter in condition for further use, and means for engaging and retaining a pair of carbon sheets for insertion between leaves in the uppermost set. 70

2. A manifolding device comprising a pad consisting of a pair of continuous sheets folded reversely back and forth to form a series of sets of leaves in quadruplicate, the sheet which forms the inner leaves of said set being transparent and the other of said sheets being opaque, a retaining clip engaging that end of the pad adjacent the free ends of the leaves in the uppermost set to yieldably maintain the pad in assembled relation, and means yieldingly urged toward said clip for retaining a double carbon strip therebetween. 75

3. A manifolding device comprising a pad consisting of a pair of continuous sheets folded reversely back and forth to form a series of sets of leaves in quadruplicate, the sheet which forms the inner leaves of said set being transparent and the other of said sheets being opaque, a retaining clip engaging that end of the pad adjacent the free ends of the leaves in the uppermost set to yieldably maintain the pad in assembled relation, means yieldingly urged toward said clip for retaining a double carbon strip therebetween, said carbon strip comprising a double faced portion directly engaged by said last named means and adapted for insertion between the second and third leaves of each set, and a single faced portion hingedly connected to said double faced portion and adapted for insertion between the third and fourth leaves of each set. 95 100

In testimony whereof I hereunto affix my signature.

GUSTAV RUDOLF GOMPF.
